UNITED STATES PATENT OFFICE

JOHN A. JOHNSON, OF WOODHAVEN, NEW YORK

RECEPTACLE CLOSURE LINING APPARATUS

Application filed November 22, 1928. Serial No. 321,179.

This invention relates to apparatus for applying linings, or sealing pads and linings, to receptacle closure caps, and relates particularly to apparatus of this character wherein the caps are successively positioned relative to punch and die mechanism for stamping disks from a web of lining material fed in interposed relation to the punch and die mechanism and a closure cap positioned relative thereto, and it is the object of the invention to provide adjustable apparatus of this character to accommodate the same for the applying or assembling of linings, or pads and linings, to caps of different size.

Another object of the invention relates to improved means for feeding a web of lining material, or webs of lining and pad forming material, to the punch and die mechanism, and comprising a pair of feed rollers and adjustable actuating means for said rollers to feed predetermined lengths of the web or webs to the punch and die mechanism for the severing of lining and pad disks from the webs for different size closure caps.

A further object of the invention is to provide improved web feeding means embodying a pair of rollers one of which is rotatably mounted in fixed bearings and the other rotatably mounted in bearings arranged to have movement toward and away from and yieldingly urged toward the first roller and positively driven therefrom, means being provided to move the second roller away from the first roller and retain it in such position to facilitate the threading of the web or webs between the rollers, and to provide improved clutch mechanism associated with the roller mounted in the fixed bearings operative to intermittently actuate the same.

Another object of the invention is to provide adjustable means to deliver different size caps to the means to transfer and position the caps relative to the punch and die mechanism.

A further object of the invention is to provide improved web feeding means embodying a pair of feeding rollers one of which rollers is yieldingly urged toward the other roller and the latter roller arranged with clutch mechanism the actuation of which is adapted to be controlled by the passage of a

cap at a predetermined point in the feeding of the caps to the punch and die mechanism by the transferring and positioning means to rotate the rollers in one direction.

Still further object of the invention resides in adjustable Geneva gear mechanism for connecting a drive shaft with the means for transferring closure caps of different size to and alining the same with the punch and die mechanism.

Further objects and advantages of the invention will hereinafter appear.

In carrying out the invention there is provided an endless or continuous cap transferring and positioning means mounted on a suitable framework in relation to closure cap supporting rails having laterally adjustable guide rails or members to adapt the same for the supporting and transferring of different size caps, and arranged with means at one end thereof to deliver different size caps thereto, said cap transferring and positioning means being adapted to be actuated intermittently by Geneva gear mechanism the operative connection between which mechanism and the cap transferring means is adjustable to adapt the cap transferring means for positioning caps of different size in alinement with punch and die mechanism, arranged with stripper means, to sever a disk or disks from a web or webs and deliver the same to a cap positioned relative to the punch and die mechanism. The web or webs are fed to the punch and die mechanism by a pair of feeding rollers intermittently actuated in synchronism with the actuation of the cap transferring means and alternately with the operation of the punch by a reciprocating slide operatively connected with the feed rollers through an over riding one-way operating clutch mechanism to rotate the rollers in one direction by the movement of the slide in one direction, and the movement of the slide being adjustable to transmit variable movement to the rollers and deliver predetermined lengths of web or webs to the punch and die mechanism to stamp disks of different size therefrom for different size caps.

Means are provided to releasably couple the roller clutch actuating mechanism with the operating slide, 100

said means being operative to normally uncouple the roller clutch actuating mechanism from the slide to render the rollers inactive to feed the web to the punch and die mechanism, and the coupling of said roller actuating means with the operating slide being controlled by caps transferred on the cap support to feed the web to the punch and die mechanism when a closure cap is positioned relative thereto. After the lining has been applied to the caps they are delivered by the transferring means from the cap support to an endless conveyor arranged at the end of the cap transferring means opposite to the end at which the caps are fed thereto and to travel in a direction transversely to the direction of travel of the cap transferring means and delivered by said conveyor to a suitable depository.

20 In the drawings accompanying and forming a part of this application Figure 1 is a plan view of apparatus embodying the invention.

25 Figure 2 is an elevational view looking at the bottom of Figure 1 portions being broken away to show essential features of the invention.

30 Figure 3 is a cross sectional view taken on the line 3-3 of Figure 1, looking in the direction of the arrows, to show the construction and arrangement of the punch and die mechanism and feeding rollers for feeding webs of lining and sealing pad material and actuating means for the rollers.

35 Figure 3a is a detail view partly in section, of the adjustable mounting of the pivot support of an operating lever for actuating means for the web feeding rollers.

40 Figure 4 is a perspective view, on an enlarged scale, of means actuated by a cap being transferred and positioned relative to the punch and die mechanism for controlling the actuation of the web feeding rollers.

45 Figure 5 is an enlarged view, partly in section, of the actuating means for the web feeding rollers and showing the means for releasably coupling the same with operating means therefor.

50 Figure 6 is a rear elevational view of the mounting of the web feeding rollers and the actuating means therefor.

55 Figure 7 is an elevational view of a one-way operating clutch mechanism for intermittently rotating the web feeding rollers in one direction.

60 Figure 8 is an end view of means to deliver the closure caps from a closure cap transporting conveyor to the cap transferring means.

65 Figure 9 is a fragmentary plan view of the cap delivery means looking at the top of Figure 8.

70 Figure 10 is a side elevation, on an enlarged scale, of the means for effecting adjustment

75 between the cap transferring means and its actuating means.

Figure 11 is a view looking at the bottom of Figure 10.

70 Figure 12 is a plan view of the right hand end portion of Figure 1 to show the arrangement of a conveyor and its actuating means for supplying caps to the cap transferring means; and

75 Figure 13 is a detail view in plan of means for guiding caps on the supply conveyor and the transferring of caps therefrom to the cap transferring means.

80 In the embodiment of the invention illustrated in the drawings closure caps C are transferred or conveyed by an endless sprocket chain 10 engaged about spaced sprocket wheels 11, 11' fixed on shafts rotatably mounted in a table T supported upon standards S. The shaft of wheel 11' is journaled in a bearing 12 slidably mounted on a bracket 12' fixed upon and extended from the end of the table, and adjustable on the bracket in a direction toward and away from the table

85 to take up slack in the chain by a tie member 13' threaded into the bracket and bearing, the tie member being secured against rotation and thereby retaining the bearing in adjusted position by a nut 13'' on the tie member abutting against the bracket. The shaft of wheel 11 is journaled in fixed bearings adjacent the opposite end of the table, said wheel mountings being such as to position the upper stretch of the chain on the same plane as the

90 surface of the table and in line with a space between a pair of cap supporting rails 13 mounted on the table by brackets 57. To transfer the caps along the cap supporting rails the chain is arranged with cap engaging

95 means in the form of abutment fingers 14 equidistantly spaced along the chain, the spacing of the fingers being equal to the diameter of the largest size cap the apparatus is capable of handling. The sprocket wheels are rotated from a continuously rotating

100 drive shaft 15 journaled in bearings in hangers 15' to extend longitudinally of and below the table and connected with a source of power by a pulley 15'' and a belt (not shown). The sprocket chain is intermittently actuated from the drive shaft through a transverse shaft 16 connected to the drive shaft by a bevel pinion and gear connection

105 17. A wheel or disk 18 fixed to said shaft is arranged with laterally extending pins 19, in the present instance two in number and disposed diametrically opposite, to successively engage in recesses 20' equidistantly spaced about and extending radially inward from the periphery of a wheel 20 loosely

110 mounted on a shaft 21 extending parallel to the shaft 16. The wheel 20 is arranged with eight of said recesses whereby two intermittent movements are imparted to said wheel upon each revolution of the wheel 18. The

5 peripheral portions of the wheel 20 between the recesses are of arcuate or concave form, as at 22, to correspond with the surfaces 24 arranged diametrically opposite on a block or plate member 23 rotatable with the wheel 18 and adapted to engage with the arcuate portions 22 of wheel 20 during the periods of rest of said wheel and hold the same against movement.

10 The wheel 20 is mounted on the shaft 21 to rotate therewith and to permit of adjustment of the wheel relative to the shaft through a gear or worm wheel 27 fixed upon the shaft 21. The wheel 20 is loosely mounted on a 15 hub of said worm wheel, as at 20', in abutting relation to an annular flange on said hub engaging in an annular enlargement or recess in the bore of the wheel 20, as at 27', the width of the flange being slightly greater than the 20 depth of the recess so that the outer side of the flange will project from the face of the wheel. To secure the wheel 20 to the hub of the worm wheel and thereby with the shaft 21 to rotate with the latter, the wheel is 25 clamped to the hub flange by washers 25 engaged on reduced threaded ends of studs 26, in the present instance three in number, threaded into and circumferentially disposed about the wheel 20 adjacent the periphery of 30 the flange 27', the washers being interposed between the face of the wheel and the shoulder of the studs formed by the reduced ends thereof and overlap the peripheral portion of the flange 27' for clamping engagement with 35 the portion of the flange projecting from the face of the wheel, the studs being arranged at the end for the application of a wrench to firmly draw the washers to the flange 27'. The conveyor or sprocket chain is operatively 40 connected with and driven from the shaft 21 by a gear 28 fixed to said shaft meshing with a gear 29 fixed to the shaft of sprocket wheel 11.

11. The adjustable mounting of the wheel 20
45 is for the purpose of adjusting the sprocket
chain whereby the fingers 14 of the chain are
moved to a predetermined position during
the periods of rest of the chain and thus
adapt the chain to the transferring and pre-
50 determined positioning of different size caps.
To effect this adjustment of the chain the
washers 25 are released to permit of rotative
adjustment of the wheel 20 relative to the
worm wheel 27 and shaft 21 and thereby ad-
55 justing the shaft for the sprocket wheel 11
and advance or retract the sprocket chain to
variably position the fingers 20 carried there-
by when the chain is brought to rest and po-
sition caps transferred by the chain centrally
60 relative to punch and die mechanism to re-
ceive a disk or lining material stamped by
said mechanism from a web of such material,
as hereinafter described.

This adjustment of the shaft 11 and sprocket chain is effected by a worm 30 ro-

tatably mounted on the side of wheel 20 meshing with the worm wheel 27 and adapted to be actuated by a crank applied to the squared projecting end of the worm shaft. By rotating the worm, with the wheel 20 released from the gear 27, wheel 20 and shaft 11 will be rotated independently of and relative to the worm wheel 27. The wheels 18 and 20 are in effect a Geneva gear mechanism and are enclosed in a housing H hingedly mounted on the table, as at 29'. 70

The caps are delivered to the cap support 13 from an endless conveyor belt 31 passed around and supported by spaced drums or rollers 32, 32'. The drum 32 is rotatably supported on a shaft 33^a fixed in and extending laterally from a bracket 34' mounted on and extended from the end of the table and is rotated from the shaft carrying sprocket wheel 11' by a sprocket wheel 32^a rotatable with said drum 32 operatively connected to a sprocket wheel 32^b fixed to the shaft carrying sprocket wheel 11' by a sprocket chain 33. The other drum 32' is rotatably supported on a shaft 33^b fixed in and extending laterally from a bracket 34 mounted on an extension of bracket 34' to have adjustment longitudinally thereof whereby to adjust the drum 32' and take up slack in the conveyor, the bracket 34 being secured in adjusted position by a screw 35 engaging a slot in the bracket and threaded into the bracket 34', the bracket 34 being adjusted and retained in adjusted position by a lead screw 36 threaded into the bracket with the end of the screw abutting the end of the extended portion of the bracket 34'. The caps are delivered onto the conveyor 31 by hand or from a chute leading from a supply hopper (not shown).

To prevent the caps from piling one upon another on the conveyor 31 and to guide the caps as they are conveyed by the conveyor to means (to be hereinafter described) for delivering the caps from the conveyor to the 110 guide supporting rails 13, a pair of guide rails 37, 37' (Figure 13) are provided to extend longitudinally of and above the lateral marginal portions of the upper stretch of the conveyor, the guide rail 37 being fixed to and carried by arms 38 extending laterally from a frame 38' mounted upon the bracket 34', and the other guide rail 37' mounted on said arms to have adjustment toward and away from the rail 37 to adapt the same for the guiding of caps of different size, this adjustable connection comprising threaded studs fixed in and extending upward from the guide rail 37' and engaging elongated slots in the arms 38 with thumb nuts threaded onto said studs, as shown at 36'. The caps are fed by the conveyor in relation to an abutment stop 39 mounted on and extended from the end of one of a pair of guide rails 56 extending parallelly of and above the outer marginal por- 115 120 125 130

tions of the cap supporting rails 13, said stop extending transversely of the path of movement of the caps transported by the conveyor 31 (Figure 9) to position the caps in relation to the means for delivering the caps from the conveyor to the cap supporting rails. To adapt said abutment stop for the alining or registering of caps of different size relative to said means for delivering or transferring the caps from the conveyor 31 to the conveyor chain 11, it is adjustably mounted which is effected by a headed screw passed through a slot in the stop and threaded into the rail 56. The stop 39 also serves as a guide in conjunction with a guide 54 arranged at the end of the guide rail 37' for the guiding of the caps as they are transferred from the conveyor 31 to the chain 11, and to adapt the guide 54 for the transferring and guiding of caps of different size it is adjustable relative to the stop 39, which is effected by the adjustable mounting of the frame 38' by engaging headed screws in elongated slots with washers interposed between the screw heads and frame, as shown at 40 in Figure 13, and threading said screws into openings 40' (Figure 12) in the extension of bracket 34'. The conveyor 31 is arranged so that one end portion will extend in parallel relation to one side and an end portion of the cap supporting rails 13.

The means to deliver or transfer the caps from the conveyor 31 to the supporting rails comprises an ejector slide 41 and an actuator slide 42 for the ejector slide mounted to have reciprocatory movement in a slideway 43 extending transversely of and fixed upon bracket 34' with the end adjacent the side of the conveyor 31. The ejector slide 41 is adapted to have movement transversely of the conveyor and is arranged above and operatively connected with the actuator slide, by a pin 44 fixed in the actuator slide 42 extended through an elongated slot 45 in the ejector slide and the slides yieldingly urged to position with the pin engaging at one end of said slot by a spring 46 connected with the pin 44 and a pin 47 fixed in the ejector slide (Figures 7 and 8). The actuator slide has reciprocatory movement of fixed extent and by the pin and slot connection between the slides movement of variable extent may be transmitted to the ejector slide by the actuator slide to adapt the same for the delivery or transferring of caps of different size from the conveyor to the cap supporting rails 13 and properly position the caps upon said supporting rails for engagement by the fingers 14 of the chain 10 of the cap transferring and positioning means. The extent of the movement of the ejector slide is controlled by an adjustable abutment, in the form of a set screw 48 threaded into a downwardly extended flange at the end of the ejector slide and

adapted to abut the outer end of the actuator slide 42.

The actuator slide 42 is operated from the drive shaft 15 by a lever 49 pivotally mounted intermediate the ends thereof on a bracket 49' fixed on one of the standards S, said lever being operatively connected with the drive shaft 15 by a link 50 pivotally and eccentrically connected at one end with a disk 51 fixed on the shaft and at the other end to one end of the lever 49, the opposite end of the lever having a link connection 52 with a projection 53 extending downward from the actuator slide 42.

The caps are guided in the lateral movement thereof from the conveyor 31 to the cap supporting rails 13 by the extended end 54 of the guide rail 37' in co-operation with the stop 39 and a guide finger 55 to extend over the caps mounted on one of the guide rails 56. To permit of the transferring of caps of different size along the cap supporting rails 13, both of the rails 56 are arranged with transverse slots 58 for the engagement of securing screws threaded into brackets 57 mounted on the table T to permit of an adjustment of the rails in a direction toward and away from the space between the cap supporting rails 13, said brackets 57 being arranged with perpendicular abutments 57' to limit the outward adjustment of said rails. The guide rail 37 may be integral with one guide rail 56, the juncture of said rails forming the abutment 39, as shown in Figure 9, and the guide rail 37' may be integral with the other guide rail 56 whereby the rails 37, 37' will participate in any adjustment of the rails 56 and adjustment of all of the side guide rails effected simultaneously.

To assemble a lining in the caps punch and die mechanism to stamp disks from a web of lining material is provided, said mechanism being arranged in alinement with and centrally above the cap supporting rails 13 to successively stamp or sever disks from the web and deliver the same into a cap positioned on the cap supporting rails in alinement with the punch and die mechanism during a period of rest of the cap transferring and positioning chain, and comprises a punch 59 carried by an arm 60 extended laterally from a vertically movable slide 61, said punch being adjustable longitudinally of the slide by extending an externally threaded stem 63 carrying the punch through an opening in the slide arm and securing said punch carrying stem in adjusted position by nuts 62 threaded onto said punch stem and impinged on both faces of the slide arm. The slide 61 is slidably mounted and guided in a standard 64 fixed on the table T. The punch carrying slide is reciprocated from the drive shaft 15 by an arm 65 arranged with a sleeve 65' loosely engaged about an eccentric 64' fixed to the drive shaft 15, said arm having a piv-

total connection 66 with the punch carrying slide 61. The punch 59 co-operates with a fixed die 67 to sever disks from the web, said die being mounted on the table by a perforated plate 68 extending transversely of and above the cap transferring and positioning chain. The severed disks are ejected from the punch and die and positioned in a cap on the cap supporting rails 13 by a stripper 10 in the form of a plunger rod 71 slidably carried in a bore of the punch carrying stem 63 and punch, said plunger having a head 72 fixed thereon and normally positioned in an enlargement of the punch bore and within the punch face by a spring 73 coiled about the end of the plunger extended from the top of the punch stem and interposed between the top punch stem securing nut 62 and an abutment 74 fixed on the upper end of the plunger 20 71, said plunger being actuated in sequence with the operation of the punch stamping a disk from the web by a kicker in the form of a lever 75 pivotally mounted in the bifurcation of a bracket 76 fixed to the top of the slide 61, one end of said lever having a head 77 to engage the plunger 71, the opposite end of the lever extending over an abutment 25 in the form of a set screw 78 threaded in the top of the standard 64, and said end of the lever adapted to engage said abutment at the terminus of the downward stroke of the punch to project the plunger head 72 from the face of the punch and stripping from the punch a disk stamped from the web and delivering it through the die to the cap on the cap support. This ejecting movement 30 of the plunger may be varied by adjusting the abutment screw 78 into or out of the standard 64. The actuation of the punch carrying slide is alternate with the actuation of the cap transferring and positioning chain.

The lining may comprise several separate layers of material, such as a bottom layer of heavy paper to form a sealing pad, and a top 45 layer of paraffined paper to prevent decomposition of the contents of a receptacle to which the closure cap may be applied, which disks are stamped simultaneously from superposed webs fed to the punch and die mechanism from separate rolls 80, 81 of such material, the roll 80 being the paraffined paper and the roll 81 the heavy or sealing pad material, to which the web 80 is superposed, and said rollers being rotatably carried in a bracket 82 fixed to the side of the table T.

The webs are fed or advanced to the punch and die by a pair of superposed rollers 83, 84 of friction gripping material, such as rubber or fabric, the rollers 83 being mounted 60 to have movement toward and away from the roller 84. The roller 84 is carried by a shaft journaled in fixed bearings in a frame 88 fixed upon the table T, and the roller 83 is carried by a shaft 85 journaled in bearing blocks 86 slidably mounted in recesses 87 in

vertical extending members of the frame 88 in alinement with the punch and die mechanism. The roller 83 is yieldingly urged into engagement with the roller 84 by coiled springs 89 arranged in the frame recesses 87 with one end of the springs seated in sockets 90 in the bearing blocks 86 and the opposite ends engaged upon pins extended downward into the frame recesses 87 from cap members 91 bolted to the frame members to span the recesses 87. To space the rollers apart for the insertion or threading of the webs between the roller the bearing blocks are connected to a cross head 92 extending between the vertical members of the frame 88 above the roller 83 and having a perforation 93 for the engagement of the hooked end of a hanger member 94 extended from a sleeve portion 95, whereby it is loosely mounted on an eccentric 96 fixed on a shaft 97 rotatably mounted in upwardly extending portions 91' of the cap members 91. To adjust the roller 83 to position it away from the roller 84 and retain it in such position the shaft 97 and thereby the eccentric is rotated by a hand lever 98 fixed to the shaft. To effect adjustments between the hanger and the carrier 92 for the roller bearing blocks 86 a set screw 99 is threaded in and extended through the hook portion of the hanger to abut the upper wall of the perforation 93 in the carrying head 92 for the bearing blocks.

To guide the webs to the feeding rollers a pair of rods 100 are fixed at one end in a post 100' fixed to and extending upward from the frame 88 parallel to one of the vertical members of the frame, the rods extending laterally from the post transversely of the line of travel of the webs and in a horizontal plane above the bite between the web feeding rollers and have adjustably mounted thereon guides for engagement of the edges of and side guiding the webs, comprising bars 101 arranged with perforations adjacent opposite ends thereof for engagement of the respective rods 100, each of the bars having one end, shown as the upper end, split or slotted, the slot extending from the end of the bars and cut through the wall of the perforation adjacent said end, the portions of the bars at opposite sides of the slot being arranged with alined perforations with a screw extended from the perforation in one member and having threaded connection with the perforation in the other member, as shown at 101' in Figure 5, to draw the split portions together and thereby clamp the guides to the bars 100.

The feed rollers are positively driven one from the other by gears 102, 103 fixed to the shafts of the respective rollers. The rollers are intermittently actuated to feed predetermined lengths of web to the punch and die mechanism, and are driven through a shaft 104 of roller 84 by an actuator slide 105

mounted to have reciprocatory movement in guideways 106 arranged in a horizontal extension 107 of the frame 88. Reciprocatory movement of variable extent is imparted to the slide to variably rotate the feed rollers to feed different lengths of web by a lever 108 arranged with an elongated slot 109 for the adjustable engagement of a block 109' loosely mounted on a reduced portion of a pivot block 110 arranged with another reduced projection extending in the opposite direction in the form of a block slidably mounted in a recess 111 extending longitudinally of an arm 112 suspended downward from the horizontal portion 107 of the frame 88. To secure the lever to the pivot block 110 there is provided a washer 110' on the block 109' between the body portion of the block 110 and the inner side of the lever and a washer 110 on a further reduced threaded portion extending from the block 109' beyond the outer side of the lever upon which a nut 115' is threaded to impinge the latter washer against the part of the pivot block upon which the block 109' is mounted to hold the lever against displacement on the pivot block. The reduced block portion having slideable engagement with the arm recess 111 has threaded connection with a lead screw 114 rotatably carried in a member 113 secured to the arm 112 to bridge the end of the recess with the screw extending longitudinally of the recess and the said block portion arranged with a reduced threaded portion for engagement of a washer 116 and nut 115 to clamp said pivot block in adjusted position in the arm slot. By loosening the lever upon its pivot support and the rotation of the lead screw, which is facilitated by a hand wheel 114' fixed to the end of said screw, the pivot block may be adjusted in the arm slot 111 and in the slot of the lever to vary the distance between the lever pivot and the connection of the lever with the slide 105 and thereby varying the extent of movement imparted to said slide by the rocking of the lever.

Oscillatory movement is imparted to the lever 108 by an eccentric 117 fixed on the drive shaft 15 through a rod 118 connected at one end to a strap 119 encircling the eccentric, and at the opposite end adjustably connected to a sleeve 120 by nuts threaded onto the rod at opposite sides of the sleeve, and the sleeve pivotally connected to the lower end of the lever. The oscillation of the lever by the eccentric 117 is in synchronism with the cap advancing movement of the cap transferring chain and alternate with the actuation of the punch.

The reciprocatory movement of the actuator slide 105 is transmitted to the web feeding rollers by a ratchet mechanism, comprising a block 121 slidably mounted in the guideway 106 at the inner end of the slide 105, said block being arranged with laterally ex-

tending ears 122 for the pivotal mounting of a latch 123 to extend over and beyond the outer end of the actuator slide 105, and having the free end arranged to form a hook 123' to engage the outer end of said actuator slide to releasably connect the block thereto and whereby the block is adapted to participate in the reciprocatory movement of the actuator slide. A rack 124 fixed to and extending forward from the block 121 meshes with a pinion 125 fixed upon the laterally extending hub of a cup shaped member 126 loosely mounted on the extended end of the shaft 104 of the feed roller 84, the flange of said member 126 encircling a head 127 fixed to the shaft 104 and arranged with recesses 128 equidistantly spaced about the periphery, in the present instance three in number, (Figure 7) the bottom wall of which recesses are of arcuate form arranged in an arc eccentric to the axis of the head, and the flange of the cap member co-operating with said recesses to form tapered sockets or chambers. Wedge members 129, which may be rollers or balls, are arranged in said sockets and yieldingly urged toward the reduced end thereof by springs 130 confined between the wedge members and the opposite end of the sockets. The recessed head is enclosed in the cup member by a perforated plate 131 (Figure 6) loosely engaged upon a hub of the head and secured to the cup member. During the forward movement of the rack the pinion 125 is rotated in the same direction moving the wedge members into impinging engagement with the peripheral wall of the cup member and the bottom wall of the head recesses, thereby coupling said head and feed roller 84 with the rack and imparting web feeding movement to the feed rollers. Upon the return movement of the rack the wedge members 129, the frictional contact thereof with the walls of the cup member and recesses are moved against the tension of the springs out of impinging engagement with the walls of the cup member and recesses and moved into the larger portion of the sockets releasing the rack from the rollers. The rack is maintained in engagement with the pinion by a roller 132 engaging the top of the rack rotatably carried by a headed stud secured in and extended laterally from a vertical member of the frame 88.

To prevent the feeding of the web to the punch and die mechanism for the stamping of a disk therefrom when there is no cap positioned relative to the punch and die mechanism, means are provided to control the coupling of the rack carrying block 121 with the actuator slide 105 to render the web feeding rollers inactive upon the actuation of the actuator slide 105. The latch 123 is normally positioned out of engagement with the actuator slide 105 to uncouple the rack carrying block 122 therefrom by a slide 133 mount-

ed to have vertical movement upon the side of the extension 107 of the frame 88, said slide being normally urged in an upward direction by a spring 134 and into engagement with a 5 bar 135 fixed upon and extended laterally from the latch, the slide 133 being of a width to engage the bar in all positions of the latch. The latch is moved into engagement with the actuator slide for operatively connecting 10 the web feeding rollers with the slide by means controlled by a cap positioned upon the cap support by the cap transferring chain and in position to be advanced to the punch and die mechanism upon the successive movement 15 of said chain, and comprises a lever 136 (Figure 4), pivotally mounted adjacent one end on the inner edge of one of the guide rails 56, said lever having an arcuate cut out portion 137 to clear a securing screw for the rail 20 56 with the opposite end of the lever arranged with a dog 138 opposite to a recess cut into the edge of said guide rail, the lever being yieldingly urged under the influence of a spring 139 to position said dog into the path 25 of movement of and for engagement by the caps as they are transferred along the cap support by the cap transferring chain, and when said chain is at rest with a cap positioned in engagement with said lever dog 30 and positioning said dog in the rail recess and rocking the lever, as clearly shown in Figure 4.

An arm 140 is extended at a right angle from the lever and laterally of the dog, said 35 arm being offset outwardly intermediate the length thereof, as at 141, whereby the outer end is arranged in a higher plane than the lever. The offset end of said lever arm is adapted to engage with a plate 142 at the 40 weighted end of a second lever 143, said plate having a portion 142' projecting downward from one corner. The lever 143 is pivotally mounted intermediate the ends on the side of the frame 88 with the opposite end bifurcated, as at 144 (Figure 3) engaging a 45 pin, as at 145, fixed in and extending laterally from the latch releasing slide 133. The lever 136 normally assumes a position as shown in dotted lines in Fig. 4 with the dog 50 138 engaging in the path of movement of the caps along the guide rails and the lever arm 140 engaging at one side of the plate projection 142 carried by the lever 143, and the latch controlling slide 133 in its raised position with the latch 123 out of engagement 55 with the slide 105, and as the slide 105 is reciprocated the movement thereof will not be transmitted to the rack carrying block 121 of the actuating means for the web feeding rollers. As caps are advanced along the 60 cap support by the cap transferring chain the passage of a cap along the portion of the cap support into which the lever dog 138 is projected the cap will engage such lever dog 65 and move the lever 136 against the action of

the spring 139 moving the lever dog into the recess in the edge of the side guide rail 56, as shown in full lines in Figure 4, and causing the lever arm 140 to ride under the projection of plate 142 rocking the lever 143 and thereby moving the latch slide 133 downward against the tension of the spring 134 permitting the hook of latch 123 to engage in the outer end of the actuator slide 105 and thereby couple the rack carrying block 121 70 with and to be moved by the actuator slide upon the next outward movement thereof, and the rack carrying the block being moved inward upon the successive inward movement of the actuator slide and thereby operating 75 the web feeding rollers to deliver the web to the punch and die mechanism. A cap is positioned on a cap support relative to the lever dog during a period of rest of the cap transferring chain, and as the web feeding rollers are actuated such cap is positioned in alignment with the punch and die mechanism to receive the disk stamped from the web. During this movement of the cap transferring chain a successive cap will be positioned relative to the lever dog 138 to actuate the lever to operate the mechanism to couple the rack carrying block with the actuator slide. However, should there be no cap on the cap support to be positioned relative to the lever dog the rack carrying block will remain uncoupled from the actuator slide and the web feeding rollers will be rendered inactive. 80

After the disks are severed from the web by the punch and die mechanism the perforated 100 web or webs are delivered over the plate 68 through openings 69 and 70 in the punch carrying slide 61 and the carrying standard 64 therefor to a discard depository, not shown.

After the disks have been positioned in the 105 caps, the caps are intermittently advanced along the cap supporting rails 13 by the cap transferring chain until the cap engaging fingers of the chain are disengaged from the caps by the movement of the chain and fingers in a downward direction over the sprocket wheel 11, the caps being advanced from said point by the forward movement of the caps on the cap support in the rear thereof which 110 are being advanced by the cap transferring chain and delivered onto an endless belt conveyor 146 passed around and supported by a pair of drums 147 rotatably mounted in bearings carried at the delivery end of the table 115 T to travel in a direction transversely of the cap transferring chain and in a direction indicated by the arrow in Figure 1, said conveyor delivering the aligned caps into a depository at the end of the conveyor (not 120 shown). The conveyor is continuously actuated from the drive shaft 15 by a sprocket chain 148 passing around a sprocket wheel 149 fixed on the drive shaft, and a sprocket wheel 150 fixed on a shaft of a conveyor sup- 125 130

porting drum 147, the chain being enclosed by a protective housing 151.

It will be obvious that various modifications may be made in construction and arrangement of parts, and that portions of the invention may be used without others, and come within the scope of the invention.

Having thus described my invention I claim:

- 10 1. In closure cap lining apparatus, a pair of laterally spaced cap supporting rails, means to deliver caps to said support, punch and die mechanism arranged in alinement with said support, an intermittently operative endless chain arranged with the upper stretch 15 to travel in the plane of the space between the cap supporting rails and having equidistantly spaced cap engaging means to move the caps along and position the same on the supporting rails relative to the punch and die mechanism, rollers for feeding a web of lining material transversely of and in interposed relation to the punch and die mechanism and a cap positioned relative thereto, said punch 20 and die mechanism being operative to stamp a disk from the web and deliver the same to the cap positioned relative thereto, means to actuate the web feeding rollers synchronously with the actuation of the cap transferring and positioning means and alternately with the punch to successively feed predetermined lengths of the web.

2. In closure cap lining apparatus as claimed in claim 1, means to adjust the 35 chain to adapt the same to position caps of different size on the support in alinement with the punch and die mechanism.

3. In closure cap lining apparatus, a cap support, continuous cap transferring and positioning means, means to intermittently actuate said cap transferring and positioning means, rails extending parallelly of and above the outer marginal portion of the cap supports to guide the caps on the support 40 and adjustable laterally to adapt the same to different size caps, punch and die mechanism arranged in alinement with the support relative to which the caps are positioned on the support by the transferring and positioning means, means to intermittently feed successive predetermined lengths of a web of lining material to the punch and die mechanism for the severing of a disk from the web and delivery to a cap positioned relative to the punch and die mechanism, means 45 to adjust the transferring and positioning means relative to its actuating means to adapt the same to aline caps of different size relative to the punch and die mechanism, and means to which the caps with linings assembled therein are delivered from the support by the transferring and positioning means.

4. In closure cap lining apparatus as 60 claimed in claim 1, means operative by a cap

on the support to control the actuation of the web feeding rollers.

5. In means for stamping lining disks from a web and assembling the same in closure caps, punch and die mechanism, intermittently operative means for feeding and successively positioning caps relative to the punch and die mechanism, a pair of rollers to feed a web of the lining material in interposed relation to the punch and die mechanism and a cap positioned relative thereto, and means to intermittently actuate said rollers in synchronism with the cap feeding means and alternately with the operation of the punch.

6. In means for stamping lining disks from a web and assembling the same in closure caps, a cap support, punch and die mechanism, a continuous chain arranged with cap engaging means to intermittently feed and position caps on the support relative to the punch and die mechanism, a pair of rollers to feed a web of lining material to the punch and die mechanism, and means to intermittently actuate said rollers in synchronism with the cap feeding means and alternately with the operation of the punch.

7. In means for stamping lining disks from a web and assembling the same in closure caps, punch and die mechanism, intermittently operative means for feeding and successively positioning caps relative to the punch and die mechanism, a pair of rollers to feed a web of lining material to the punch and die mechanism, means to intermittently actuate said rollers in synchronism with the cap feeding means and alternately with the operation of the punch, and lever means to control the operation of the rollers actuated by the passage of caps at a predetermined point along the support.

8. In means for stamping lining disks from a web and assembling the same in closure caps, punch and die mechanism, intermittently operative means for feeding and successively positioning caps relative to the punch and die mechanism, a pair of rollers to feed a web of lining material to the punch and die mechanism, a rack supported to have reciprocatory movement and operative in synchronism with the cap feeding means, a pinion meshing with the rack, and means to couple the pinion with and impart web feeding movement to the rollers by the movement of the rack in one direction.

9. In means for stamping lining disks from a web and assembling the same in closure caps as claimed in claim 8, a reciprocatory slide, a latch pivotally carried by the rack support to couple the rack with the slide to transmit the movement of the slide to the rack, means engaging the latch normally urged to position to move the latch out of engagement with the slide and uncouple the rack from the slide, and means operatively

connected with the means to move the latch out of engagement with the slide and having a part extending into the line of passage of the caps on the support to be engaged by a cap on the support to actuate the means to move the latch out of engagement with the slide and permit the latch to engage the slide and couple the rack with the slide.

10. Means for stamping lining disks from a web and assembling the same in closure caps as claimed in claim 8, wherein the reciprocating slide is actuated by a lever, and an adjustable pivot support for said lever adapted to vary the movement of the lever and thereby the travel of the slide to feed different lengths of the web for different size caps.

11. In means for stamping lining disks from a web and assembling the same in closure caps, punch and die mechanism, intermittently operative means for feeding and successively positioning caps relative to the punch and die mechanism, a pair of rollers one positively rotated from the other to feed predetermined lengths of web to the punch and die mechanism and one roller mounted to have movement toward and away from the other roller, and means to intermittently rotate the rollers in synchronism with the actuation of the cap transferring and positioning means and alternately with the operation of the punch and die mechanism.

12. In means for stamping lining disks from a web and assembling the same in closure caps, punch and die mechanism, intermittently operative means for feeding and successively positioning caps in alignment with the punch and die mechanism, a pair of rollers to feed predetermined lengths of web of lining material to the punch and die mechanism, means to intermittently actuate said rollers in synchronism with the cap feeding means and alternately with the operation of the punch, and stripper means carried by the punch and die mechanism to strip a severed disk from, and engage it in a cap positioned relative to, the punch and die mechanism and actuated independently of and in sequence with the operation of the punch.

13. In means for stamping lining disks from a web and assembling the same in closure caps as claimed in claim 8, a reciprocating slide, a latch pivotally carried by the rack support to couple the rack with the slide to transmit the movement of the slide to the rack, means to normally disengage the latch from the slide to uncouple the rack therefrom, a pivoted lever having an operative connection with the means to move the latch out of engagement with the slide, a pivotally supported dog having an operative connection with the lever arranged and normally urged to position to extend into the line of passage of the caps on the cap support for engagement of and to be moved by a cap on the support

to rock the lever and actuate the means to move the latch out of engagement with the slide and permit the latch to engage and couple the rack with the slide to actuate the rack and web feeding rollers from the movement of the slide.

14. Means for stamping lining disks from a web and assembling the same in closure caps as claimed in claim 12, wherein the stripper means comprises a plunger slidably mounted in and one end extended from the upper end of the punch and urged in a direction to position the opposite end of the plunger within the punch, said plunger participating in the movement of the punch and adapted to have movement independently of the punch, and means to positively actuate the plunger in sequence to the operation of the punch to project the plunger beyond the face of the punch and strip a disk stamped from the web from the punch and die mechanism and deliver it into a cap positioned relative to the punch and die mechanism.

15. Means for stamping lining disks from a web and assembling the same in closure caps as claimed in claim 5, wherein one of the web feeding rollers is mounted to rotate in fixed bearings, and the other roller rotatably mounted in a frame to have movement toward and away from and yieldingly urged toward the other roller, and one roller operatively connected with the roller actuating means and with the other roller to positively rotate the same, and means to adjust the roller carrying frame with the roller carried thereby out of engagement with the other roller and retain it in such position.

16. Means for stamping lining disks from a web and assembling the same in closure caps as claimed in claim 8, wherein the pinion of the roller actuating means is loosely mounted axially of one roller and operatively connected with the roller by a one-way operating clutch mechanism comprising a head rotatable with the one roller arranged with recesses spaced about the periphery with the bottom of the recesses arranged in an arc eccentric to the axis of the head, and a cup member rotatable with the pinion enclosing the head and co-operating with the head recesses to form arcuate tapered sockets, and wedge members in said sockets adapted to wedge the cap member to the head in one direction of movement of the pinion and cup member imparted thereto by the rack and transmit said movement to the rollers and release the cap member from the head in the reverse movement of the pinion imparted thereto by the rack.

17. In closure cap lining apparatus, a cap support, cap transferring and positioning means, adjustable guide rails extending parallel to the cap support and positioning means to engage opposite sides of the cap, punch and die mechanism in alignment with the cap support, a pair of rollers to feed pre-

determined lengths of web of lining material to the punch and die mechanism, means to actuate said rollers in synchronism with the actuation of the cap transferring and positioning means, means to operate the roller actuating means, means to connect said operating means with the roller actuating means operative to normally uncouple said operating means from the roller actuating means 5 and having a part pivotally mounted on a guide rail at the side of the cap support and normally urged to position to engage in the path of movement of the caps on the cap support to be engaged by the passing caps 10 to actuate the connecting means to couple the operating means with the roller actuating means. 15

18. Closure cap lining apparatus as claimed in claim 1, wherein the means for delivering the caps to the cap support, comprises a slotted ejector slide arranged with an adjustable abutment, and an actuator slide having a pin 20 engaging in the slot of the ejector slide to operatively connect the slides, and the actuator slide adapted to co-operate with the abutment to transmit variable movement to the ejector slide relative to the movement of the actuator slide. 25

19. In means for stamping lining disks 30 from a web and assembling the same in closure caps as claimed in claim 8, a reciprocatory slide to actuate the rack, and adjustable means to actuate and vary the reciprocatory movement of the slide, comprising a slotted lever having an operative connection at one 35 end with the slide, a slotted bracket, a lead screw rotatably mounted on the bracket to extend parallel of the slot therein, a pivot adjustably mounted in the slots of the bracket 40 and lever with which the lead screw has threaded connection, and means to rock the lever. 45

Signed at New York city, in the county of New York and State of New York, this 25th day of October, A. D., 1928.

JOHN A. JOHNSON.
